PAUL KUBELKA, OF PRAGUE, CZECHOSLOVAKIA, ASSIGNOR TO KREBS PIGMENT & COLOR CORPORATION, OF NEWARK, NEW JERSEY, A CORPORATION OF DELAWARE

METHOD OF DISSOLVING TITANIUM TETRACHLORIDE IN AQUEOUS SOLVENTS

No Drawing. Application filed February 12, 1932, Serial No. 592,656, and in Germany February 27, 1931.

The present invention relates to the production of solutions containing titanium chloride and comprises introducing anhydrous titanium tetrachloride into the body 5 and below the surface of an aqueous solvent.

In the preparation of hydrochloric acid 10 solutions containing titanium by mixing titanium tetrachloride with water or with an aqueous solution, local overheating usually occurs due to the high heat of solution which results in an evaporation of titanium tetrachloride and consequent loss of this material.

The volatilization losses can be reduced by a vigorous agitation of the solvent but can 15 not be entirely avoided in this manner.

I have found that the losses of evaporation can practically completely be avoided if the titanium tetrachloride is introduced below the surface of the suitably agitated solvent.

This may be accomplished by using one or 20 more submerged feed pipes for the titanium chloride. It was unexpectedly found that no clogging up of these feed pipes by titanium oxygen compounds or titanium oxychlorides 25 takes place or that the relatively small pressure of a titanium chloride column of a few decimeters is sufficient to remove such precipitates from the pipes. I obtain in this manner of introducing the titanium tetrachloride into the solvent, particularly when the solvent is simultaneously vigorously agitated, a much more uniform distribution 30 of the heat as has been achieved up to the present time by the usual introduction of the titanium chloride on the surface of the solvent. The hydrochloric acid gas and steam which are evolved in this operation are practically free from titanium tetrachloride.

I further found it advisable, in this manner 40 of introducing titanium tetrachloride into a solvent, to pass through these submerged feed pipes a current of dry air or other inert gas together with the titanium tetrachloride whereby not only the backing up of the titanium chloride in the pipes is prevented, but this current of air further minimizes the 45 danger of clogging up the pipes by precipitates.

As solvents for the tetrachloride, I can use, 50 besides water, particularly hydrochloric acid

and dilute solutions of titanium tetrachloride. I can also make the dissolution of the titanium tetrachloride in a continuous manner by simultaneously introducing into a body of an aqueous solvent the titanium chloride and 55 the solvent each of the two through one or more separate submerged feed pipes. The dissolution vessel is also provided with an overflow so that the freshly formed titanium chloride solution is constantly removed. In 60 this case also I can add a little air to the stream of titanium tetrachloride introduced. The rate of addition of the titanium tetrachloride and that of the water, hydrochloric acid, titanium chloride solution or other solvent, is regulated according to the desired concentration of the titanium chloride solution. Evaporation losses of tetrachloride are in this 65 case also, particularly when the solvent is vigorously agitated practically avoided.

I claim:

1. In a process for the preparation of a titanium chloride solution, the step which comprises introducing titanium tetrachloride into an agitated aqueous solvent below the 70 surface of said solvent.

2. In a process of preparing titanium chloride solutions, the step which comprises jointly introducing titanium tetrachloride and an inert gas through a submerged feed 75 pipe into an aqueous solvent below the surface of said solvent.

3. In a process for the preparation of an aqueous titanium chloride solution, the steps which comprise introducing separately and continuously through submerged feed pipes titanium tetrachloride and an aqueous solvent into a body of an aqueous titanium chloride solution below the surface of said solution continuously withdrawing from the 80 said body titanium chloride solution and regulating the rate of introduction of said titanium tetrachloride and said solvent so as to give the desired concentration of titanium chloride in the solution.

In testimony whereof, I affix my signature.
PAUL KUBELKA.
